UNITED STATES PATENT OFFICE.

GEORGE W. WILLIAMS, OF ELIZABETH, NEW JERSEY.

DESIGN FOR A SOAP-DISH.

SPECIFICATION forming part of Design No. 19,668, dated February 25, 1890.

Application filed January 18, 1890. Serial No. 337,388. Term of patent 7 years.

To all whom it may concern:

Be it known that I, GEORGE W. WILLIAMS, of Elizabeth, Union county, New Jersey, have invented and produced a new and original Design for Soap-Dishes, of which the following is a specification, reference being had to the accompanying drawings, forming a part thereof.

Figure 1 is a perspective view of my improved soap-dish; Fig. 2, a longitudinal sectional view thereof, taken on the line $x x$ of Fig. 1; Fig. 3, a cross-sectional view on the line $y y$ of Fig. 2; Fig. 4, a cross-sectional view on the line $1 1$ of Fig. 2.

The leading feature of my design consists of the two receptacles A and a central receptacle B, supported on a back C. The receptacles A are substantially rectangular in form, and are provided with reticulated bottoms D, inclined at an angle relative to the

back C, as in Fig. 3, and the receptacle substantially circular is provided with a reticulated bottom D'. The back C is divided into three panels or portions E and E', the former over the receptacles A, and having corrugations or ridges e thereon extending substantially vertical, while the panel E' over receptacle B is provided with ridges or corrugations f, arranged in fan shape or on lines radiating from a center below the top of said receptacle. The top of panel E' is also slightly lower than panel E, as shown.

What I claim is—

The design for a soap-dish herein shown and described.

GEORGE W. WILLIAMS.
